UNITED STATES PATENT OFFICE.

ANTHONY DANIELS, OF NEWARK, NEW JERSEY.

MEANS FOR SEALING CONTAINERS.

Application filed February 18, 1924. Serial No. 693,446.

This invention relates to improvements in means for sealing containers. More particularly, it is directed to apparatus for effecting a closure on the ends of flexible tube receptacles such as are in common use for holding fluid or plastic materials like dental cream, soap, paints, medicinal preparations, and the like.

One object of the invention is to provide a mechanism or apparatus of the character described which shall operate to effect an improved positive closure for tubes of the character described in a simple and highly efficient manner.

A further object is to provide an apparatus or mechanism of the character described which shall be adapted for use alike with tubes made of inelastic metallic alloys composed of lead, tin, and the like, as well as tubes made of celluloid compounds or the like material, which are neither sufficiently plastic to stay folded where the sides of the tube are pressed together and the bottom edge folded in to form a seal, nor suitable to hold a clip over such seal by pressing same into the material of the tube.

Other objects of the invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawing, in which is shown one of the various possible embodiments of this invention,

Fig. 1 is a view in side elevation of the main portion of a sealing apparatus embodying my invention showing a clip in place ready to receive a tube end;

Fig. 2 is a view in front elevation corresponding to Fig. 1;

Fig. 3 is a sectional view taken on line 3—3 of Fig. 1 showing the means for operating the front movable clamp arm through the plunger;

Fig. 4 is a top view corresponding to Fig. 1;

Fig. 5 is a sectional view taken on line 5—5 of Fig. 1 showing the means for operating the back movable clamp arm and ejecting means;

Fig. 6 is a view in side elevation of a frag-

mentary portion of the apparatus illustrated in Fig. 1 showing the clamping of the clip and the tube-end and the bending of the clinched portion prior to the folding thereof; 60

Fig. 7 is a view in side elevation similar to Fig. 6 but showing the clamping means released and the plunger finishing the folding operation to seal the tube end; and

Fig. 8 is a fragmentary sectional view 65 taken on line 8—8 of Fig. 2 showing the feeding track and pusher for the clip.

Referring in detail to the drawings, the embodiment of the invention there illustrated comprises a base-frame 10 supporting 70 an upright member 11, the upper end thereof forming a bearing 12 for a main drive-shaft 13, which may be driven by any suitable source of power, not shown. A beveled gear 14 is fastened to shaft 13 and meshes with a similar gear 15 secured on the upper end of a vertically extending driven-shaft 16 supported in a bearing 17 mounted on the rear side of the upright member 11 as shown in Fig. 1. 75

Rigidly mounted on the front free end of shaft 13 is a cam 18 which is effective on rotating shaft 13 to slide a plunger 19 vertically downward in a guideway cut in member 11 against the normal upward pressure of springs 20 set between the under side of plunger 19 and base 10 as shown in Figs. 1 and 5. Forwardly extending from the lower portion of plunger 19 is a pressure-head 21 having a groove 22 on the bottom side thereof. A fixed supporting ledge 23 projects forwardly of the base 10 to extend under head 21, and a groove 24 in ledge 23 may be provided in alignment with groove 22 on head 21 to hold a closure clip 25 in position 90 for receiving the end portions of a tube 26 to be sealed. The clip 25 is normally J or hooked shaped having legs 25^a and 25^b of unequal length, the former being the longer, and said clip 25 fits with its bent portion 100 in groove 22 and the free end of leg 25^a in groove 24 as shown in Fig. 1.

Pivoted to swing on lugs 27 also projecting from the front side of plunger 19 is a clamp arm 28, the lower end thereof being urged 105 forwardly by a spring 29 fastened to one of the lugs 27 by a screw 30. To actuate the lower end of arm 28 rearwardly, the upper end thereof may be forced forward by a cam-rod 31 moving in a bushing 32 secured in plunger 19. The rear end of rod 31 may be provided with a cam roller 33 110

which rides on cam 34 fast on driven-shaft 16. Figs. 1 and 3 plainly show the means whereby the rotation of cams 34 on shaft 16 will cause the lower end of arm 28 to swing rearward and the spring 29 to furnish means for the return movement. Cams 34 may be provided with a wide bearing face to accommodate the movement of the end of cam-rod 31 with the plunger 19.

10 A rear clamp end or ejecting piece 35 may have a push rod 36 extending rearwardly thereof which passes through the lower portion of upright member 11 below the plunger 19 and between springs 20. A rod 36 is urged rearwardly by a shaped flat spring 37, one end thereof being fastened to member 11, and the other adjustably anchored to the free end of rod 36. A pivoted bearing piece 38 is interposed between the rod 36 and a cam 39 rigidly mounted on shaft 16. Figs. 1 and 5 plainly show the means whereby the rotation of cam 39 will cause the clamp end on ejecting piece 35 to slide forward, and the spring 37 to furnish means for effecting the return movement.

The closure operation may now be described. Let it be assumed that the machine parts are in the positions shown in Figs. 1, 2 and 4 with a clip 25 between grooves 22 and 24. The end portions of a tube 26 with its sides pressed together is inserted up into the bend of clip 25. Drive shaft 13, through gears 14 and 15 will rotate shaft 16 with the cams 34 and 39. Cam 34 will force the lower end of clamp arm 28 rearward to firmly clinch the end portion of tube 26 between the legs 25^a and 25^b of clip 25, see Figs. 1, 3 and 6. Rear clamp end 35 has a V-shaped surface 35^a against which the leg 25^a of clip 25 bears and during the above clinching operation the clip 25 and the end portion of tube 26 is bent to conform with the shape of surface 35^a as a result of the pressure exerted by the co-acting surface 28^a on clamp arm 28 as shown in Fig. 6. Further rotation of shafts 13 and 16 releases the clamp arm 28 and clamp end 35 from the action of the cams 34 and 39 respectively, and permits the spring 29 to swing arm 28 forward and spring 37 to slide end 35 rearwardly away from the clip 25 and tube 26, which is meanwhile supported in the grooves 22 and 24. As soon as clamping elements 28 and 35 have been moved from under pressure head 21, the cam 18 is arranged to force the plunger 19 down to fold the clinched portion of the clip 25 and end portion of tube 26 to form a seam as shown in Fig. 7. Further rotation of shaft 13 releases the plunger 19 from the action of cam 18 and permits springs 20 to return the plunger 19 and pressure head 21 to their initial position shown in Fig. 1. The upward movement of head 21 is followed by a forward movement of clamp end 35 to its initial position, thus ejecting the finished

tube 26. The bottom rear portion of arm 28 may be cut away at 28^b to allow free passage of the tube when ejected.

A new clip is now inserted in grooves 22 and 24, and the operation repeated.

Means is provided for automatically feeding a clip 25 into proper position for clamping and may include a magazine 40 for holding a supply of clips in a stack as shown in Fig. 2, a guideway or track 41 forming a part of a supporting bar 41^a extending under magazine 40 and in alignment with the grooves 22 and 24, and a pusher 42, which is slidingly oscillated on track 41 by means driven from shaft 16. The latter means may comprise a cross-head 43 to which pusher 42 is secured, a pivoted crank member 44 for operating the cross-head 43, and a bell-crank 45 pivoted at one end to the base 10 and carrying on the other end a cam roller 46 which rides on a cam 47 mounted over cam 39 to rotate with shaft 16. A screw 48 which preferably is adjustable may be threaded into crank 45 to bear against member 44. On movement of crank 45 outwardly from shaft 16 due to the action of cam 47, member 44 will be forced to travel therewith and will slide cross-head 43 and pusher 42 to the left looking at the machine as shown in Fig. 2. Further rotation of shaft 16 releases crank 45 from the action of cam 47 and permits the retractile spring 49 fastened between base 10 and member 44 to swing the latter to the right with the cross head 43 and pusher 42. An adjustable stop in the form of a screw 50 threaded into upright member 11 may be provided to limit the swing movement of member 44 to the right.

The feeding of a clip 25 into grooves 22 and 24 is timed to take place immediately after the ejection of the tube 26 as described, the position of the parts being then as shown in Fig. 2. During the closure operation, the pusher 42 is slid to the right until the forward end thereof frees the outlet of the magazine 40. The lower clip 25 which previously rested on the upper side of the pusher 42 drops down on rail 41 and after the closure operation is completed is fed and guided into the grooves 22 and 24 ready to be applied to the next tube.

Briefly, the arrangement and combination of parts are such that a clip is clamped over the end portion of a tube, bent and folded to form a seam, the tube ejected and another clip fed into position in proper sequence for continuous operation.

It will thus be seen that there is provided a device in which the several objects of this invention are achieved and which is well adapted to meet the conditions of practical use.

As various possible embodiments might be made of the above invention and as various changes might be made in the em-

bodiment above set forth, it is to be understood that all matter herein set forth or shown in the accompanying drawings is to be interpreted as illustrative and not in a limiting sense.

Having thus described my invention, I claim as new and desire to secure by Letters Patent:—

1. A machine for effecting a closure on an end of a collapsible tube with a clip comprising means for retaining the clip, means for clamping together the sides of the tube end between the sides of the clip, and means for thereafter folding the clinched clip and tube end portion to form a seam.
2. A machine for effecting a closure on an end of a collapsible tube with a clip, comprising means for clamping the sides of the tube end between the sides of the clip and for thereafter folding the clinched clip and tube end portion to form a seam, parts of said clamping means serving to eject the tube after completing the closure.
3. A machine for effecting a closure on an end of a collapsible tube end with a clip comprising means for clamping together the side of the tube end between the sides of the clip, and for thereafter folding the clinched clip and tube end portion to form a seam, and means for feeding clips to parts of said first mentioned means in position to receive the tube ends in proper sequence for continuous operation.
4. A machine for effecting a closure on an end of a collapsible tube end with a clip comprising means for clamping together the side of the tube end between the sides of the clip and for folding the clinched clip and tube end portion to form a seam, parts of said clamping means serving to eject the tube after completing the closure, and means for feeding in position to receive the tube ends in proper sequence for continuous operation.
5. A machine for sealing an end of a collapsible tube with a clip comprising means for retaining the clip, two movable members for clamping together the sides of the tube end between the sides of the clip, and means for thereafter bending the clip and the clinched portion of the tube preparatory to folding thereof to form a seam.
6. In a machine for effecting a closure on an end of a collapsible tube with a clip, the combination of means for holding the clip in position to receive the pressed together sides of the tube end, a magazine for holding a supply of clips, and means for feeding one clip at a time from the magazine to the holding means in sequence for continuous operation.
7. A machine for sealing an end of a collapsible tube with a clip comprising means for retaining the clip, two movable members for clamping together the side of the tube end between the sides of the clip and for

bending the clinched portions preparatory to folding thereof, and a reciprocable pressure head coacting with a relatively fixed part of the machine to fold the bent clinched portion to form a seam.

8. A machine for sealing a tube end with a clip comprising two movable members for clamping the clip to the tube end and for bending the clinched portion preparatory to folding thereof, and a movable pressure head coacting with a relatively fixed portion of the machine to fold the bent clinched portion to form a seam, one of said movable members arranged to eject the tube after completing the closure.

9. A machine for sealing a tube end with a clip comprising two movable members for clamping the clip to the tube end and for bending the clinched portion preparatory to folding thereof, and a movable pressure head coacting with a relatively fixed portion of the machine to fold the bent clinched portion to form a seam, and grooves in the said head and said machine part for holding the clip in place.

10. In combination with a machine for effecting a closure on a tube end with a clip having a clip holding means, of a magazine for holding a supply of clips, and means for feeding one clip at a time from the magazine to the holding means in sequence and position for continuous operation, said feeding and positioning means comprising a track and a pusher on the track for moving a clip.

11. A machine for effecting a closure on an end of a collapsible tube with a clip comprising means for clamping together the sides of the tube end between the sides of the clip and for folding the clinched clip and the tube end portion to form a seam, and a magazine for holding a supply of clips, and means for feeding one clip at a time from the magazine to the clamping and folding means in sequence and position for continuous operation.

12. A machine for sealing a tube end with a clip, comprising two movable members for clamping the clip to the tube end and for bending the clinched portion preparatory to folding thereof, and a movable pressure head coacting with a relatively fixed portion of the machine to fold the bent clinched portion to form a seam, there being grooves in the said head and said machine part for holding the clip in place, a magazine for holding a supply of clips, means for feeding one clip at a time from the magazine and for positioning the clip in the grooves, and means for controlling the sequence of the movement of the elements of the machine to permit continuous operation.

13. A machine for sealing a tube end with a clip, comprising two movable members for clamping the clip to the tube end and for bending the clinched portion preparatory to

- 5 folding thereof, and a movable pressure head coacting with a relatively fixed portion of the machine to fold the bent clinched portion to form a seam, there being grooves in the said head and said machine part for holding the clip in place, a magazine for holding a supply of clips, means for feeding one clip at a time from the magazine and for positioning the clip in the grooves, and

10 means for controlling the sequence of the movement of the elements of the machine to permit continuous operation, said feeding and positioning means comprising a track and a pusher on the track for moving a clip.

15 14. A machine for sealing a tube end with a clip comprising two movable members for clamping the clip to the tube end and for bending the clinched portion preparatory to folding thereof, and a movable pressure head coacting with a relatively fixed part of the machine to fold the bent clinched portion to form a seam, and a magazine for holding a supply of clips, and means for feeding one clip at a time from the magazine to the clamping and folding elements and means for controlling the movable machine elements to permit continuous operation.

20 15. A machine for effecting the closure for sealing a tube end comprising means for holding a folded clip while the tube-end is inserted in the bend thereof, and means for clamping the clip and tube-end together and for thereafter making a fold in the clinched portion.

25 16. A machine for effecting the closure, for sealing a tube end comprising means for holding a folded clip while the tube-end is inserted in the bend thereof, and means for clamping the clip and tube-end together and for making a fold in the clinched portion, and means for ejecting the tube after completing the closure.

30 17. A machine for effecting the closure, for sealing a tube end comprising means for holding a folded clip while the tube-end is inserted in the bend thereof, means for clamping the clip and tube-end together, and for making a fold in the clinched portion, and mean for feeding and positioning the

operatively positioned to effect the complete closure operation while the tube is in a relatively fixed position.

24. A machine for effecting a closure for sealing an end of a collapsible tube with a folded clip comprising means for clamping together the sides of the tube end between the folded sides of the clip and partially bending the clinched portions of the tube and clip, and means for folding said bent clinched portions to form a seam.

25. A machine for effecting a closure for

sealing an end of a collapsible tube with a folded clip comprising means for clamping together the sides of the tube end between the folded sides of the clip, said means serving to concomitantly partially bend said clinched portions of said tube and clip, and means actuated after said bending operation for folding said bent clinched portions to form a seam.

In testimony whereof I affix my signature.

ANTHONY DANIELS.
